Application August 6, 1954, Serial No. 448,322

5 Claims. (Cl. 25—24)

This invention relates to turning articles of clay-ware such for example as cups.

According to the present invention the full height of the surface of the article which is to be turned is traversed by a tool which is divided into separate sections which are simultaneously in action upon different parts of the article during the advance of the tool.

According to another aspect of the invention a clay article is subjected to the action of turning means which removes the greater part of the material to be cut away and is then subjected to the action of finishing means which completes the turning operation, both the turning means and the finishing means being advanced upon the article in directions substantially tangential to its surface.

According to a further aspect of the invention a turning tool divided into separate sections is advanced slowly upon the surface of the article in a substantially tangential direction and at a slow speed, the sections of the tool being in action simultaneously upon different parts of the article and the article is next subjected to the action of a finishing tool which acts upon the surface of the article also in a substantially tangential direction but which is advanced at a higher speed.

Preferably the articles are carried by a series of chucks or supports through a predetermined path, to take them successively through the turning and finishing stations.

The articles may next be subjected to the action of a foot-turning tool which acts upon the base, and possibly also an edge-rounding tool which finishes the rim of the articles.

When a fragile article such as clay cup is being turned it is obviously an operation of great delicacy in order to avoid damage to the article. It is necessary to have the tool making a progressive traverse across the surface of the cup; it does not engage with the full height of the cup at one instant, but begins at one end and finishes at the other as it finally moves clear. Thus it can be seen that in making this traverse the tool may advance by certain distances varying according to the dimensions of the article. A possible figure for this distance of travel of the tool when turning a cup of ordinary size might be given by way of example, as two inches. Now the speed of advance of the tool is limited by practical considerations arising out of the fragile nature of the article; if the tool advance is too fast the article will be damaged. This combination of speed and distance of tool travel is the limiting factor in the output of a turning machine where hitherto the main turning operation has been done by one tool. By the present invention we divide the main turning tool into two or even more sections, so that when one section first engages with the article near the top (or bottom as the case may be) the other section engages more or less simultaneously with the article about half way down. Thus the distance which the tool has to travel in making its traverse of the full height of the cup is halved. Moreover by first performing a rough turning operation and secondly a finish-

ing operation the time factor is further reduced since both operations can be done at one time, the articles being carried successively through the turning and finishing stations, and when the further operations on the foot and rim of the article are required these can be done at a third station.

A constructional form of the invention will now be described with reference to the accompanying drawings, in which:

10 Figure 1 is a half sectional elevation of a turret head, with associated parts.

Figure 2 is a plan of a Geneva mechanism for imparting intermittent limited rotary movements to the turret head.

Figure 3 is a plan showing the disposition of a series of chuck assemblies carried by the turret head together with means for rotating them in certain positions.

Figure 4 is a general view of the tool mechanisms showing how workpieces are loaded and processed.

20 Figure 5 is a plan showing traverse mechanism for turning and finishing tool assemblies.

Figure 6 is a vertical section showing details of the driving mechanism for these tool assemblies.

The machine shown comprises a bench or table shown broken away at 10 in which a central vertical shaft 11 is mounted in journals 12, 13 and thrust race 14 and has fixed on it a spider 15, see Figure 2, whose periphery is formed with alternate curved depressions 16 and deep narrow slots 17. A cam 18 rotating continuously by means of a spindle 19 driven by any suitable gearing from an electric motor not shown in the drawings is mounted alongside the spider. The cam 18 carries a roller 18^a at one side and diametrically opposite is profiled to conform to the depressions 16 in the spider 15. The cam 18 and spider thus form a Geneva escapement by which the roller 18^a engaging with one of the slots 17 imparts a part-rotary movement amounting in the example shown to one-sixth of a circle, to the spider, followed by an interval of lost motion while the profiled part of the cam rides round the next depression 16. In this way the main vertical shaft 11 is intermittently rotated by a limited amount, say 60°. The shaft 11 has fastened to it a turret comprising a series of radiating arms 20, in the example shown six, spaced 60° apart. Each arm

45 carries a chuck assembly, indicated generally by the letter C. There are thus six chucks, see Figure 3, and each of them has associated with it a belt pulley 24, by which rotation about its own vertical axis can be imparted to each chuck, in three of the six stations to which the chucks come. The station S¹ is a loading station where a workpiece W is fitted to a chuck. The station S² is the first processing station where the side surface of the workpiece is mainly turned. The station S³ is the second processing station where the side surface

55 of the workpiece is finished. The station S⁴ is a trimming station where the foot and rim of the workpiece are trimmed off to a finished contour. The station S⁵ is not related to the present invention but is used for fitting a handle to the workpiece if desired. The station S⁶ is the unloading station where the workpieces leave the chucks. In the turning, finishing and trimming stations S², S³ and S⁴ respectively, the chucks rotate by the action of a belt 25 engaging with the pulleys 24. The belt 25 is carried on fixed idle pulleys 26, an adjustable idle pulley 26^a and a driving pulley 27 operated by an electric motor not shown in the drawings. The idler 26^a is carried by an arm 29 which is swivellably adjustable to swing the pulley 26^a for adjusting the tension of the belt 25. The workpiece is held on to the chuck during the

60 circuit from the station S¹ to station S⁶ by vacuum action applied to the chucks through pipes 21 but this part of

the apparatus forms the subject of our co-pending application No. 448,334 and need not therefore be described here. Referring now to the turning and finishing operations, see particularly Figures 4 and 5, a tool carriage 40 is supported on a pivot 41 mounted on a bracket 42 carried by a collar 43 secured around the central column 44. The carriage 40 is arranged to make limited pivotal movements in an arc which is approximately, although not exactly, concentric with the circular chuck path. This movement of the carriage is effected by a linkage 45 and cam follower 46 operated by a cam 48, and the cam is arranged and driven so that each time a chuck arrives and comes to rest in the turning station S², rotating about its own axis, the linkage 45 turns a spindle 49 which operates a fork 49^a engaging a pin 49^a fastened to the tool carriage 40; the tool carriage 40 therefore begins to swing in an arc, and this movement of the carriage effects the turning traverse of the turning tool. This tool is adjustably and interchangeably mounted on the carriage 40, outside the circular path of the chucks, by means of a tool holder 51 and bracket 52 slidably located in a guide block 53, and the tool is divided vertically into two separate portions 55, 56, one of which 55 deals with the upper half of the article while the other 56 deals simultaneously with the lower half, the traverse being progressive and the tool movement in an arc but approximately tangential to the surface of the workpiece W. By this action the surface of the article is roughly turned and at the conclusion the chuck moves on clear of the tools, and the tool carriage 40 swings back again to its original position by the action of a spring 58 in readiness for the next operation on the next article to arrive. Meanwhile the same movements have been performed by a second tool carriage 60 which is similarly mounted and attached to the first one by a connecting rod 61 pivoted to an operating lever 62 mounted on a pivot 63 and connected to the second tool carriage by an adjustable driving pin 64 working in a slot 65. By this arrangement the movement of the second tool carriage 60 is further and faster than the first one 40, and the tool 70 which it carries is a single tool. This single tool 70 acts upon the full height of an article at the station S³ in the same time as the divided tool 55, 56 aforesaid has acted upon it, so that the second tool 70 performs a finishing operation on the article which has already passed through the turning station S². The article is next carried on to the next station S⁴, in which there are two tools 73, 74, Figure 1, each adjustably carried by one of a pair of rocking levers 75, 76 operated by adjustable tappets 77, 78 and push rods 79, 80 from a double cam 81 which is adapted to raise and lower the push rods 79, 80 as required, and which are driven by means not shown. One tool 73 is thereby lifted up pivotally into contact with the foot of the article and turns the base portion to the desired contour while the other tool 74 is lowered pivotally into contact with the rim of the article and imparts the desired rounded contour thereto. The operating rods and tools are supported by a bracket 82 and posts 83, 84. This completes the turning and trimming operations and the articles move on to station S⁵ and then to station S⁶. The tools 55, 56, 70 will be designed to suit the particular workpiece being dealt with, each tool being preferably set at an angle to the axis of rotation of the workpiece in order to achieve a progressive traverse of the surface of the workpiece and also set at an angle to its line of advance in order to obtain a satisfactory cutting action on the clay.

We claim:

1. A machine for turning articles of clayware comprising a chuck for supporting the article, means for

rotating the chuck, a tool mechanism including a profiled turning tool located at an angle to the axis of rotation of the article and to the line of advancement of said tool, and means for moving the tool mechanism in a curved path so that the turning tool travels in a curved path and tangentially relative to the surface of the article and progressively engages the article initially at one part of its height and successively thereafter engages other parts along its height whereby the surface of the article is progressively turned.

2. A machine as in claim 1, in which the tool mechanism is pivotally mounted to move in a circular arc, and the tool is carried thereby to move in a circular arc intersecting the article.

3. A machine as in claim 2, in which the axis of rotation of the chuck is parallel to the pivot axis of the tool mechanism, and the tool is located on the tool mechanism to engage the article at the side thereof remote from the said pivot axis.

4. A machine for turning articles of clayware comprising a chuck for supporting the article, means for rotating the chuck, a tool mechanism including two profiled turning tools whose aggregate profile is that required to produce the contour intended on the article, each turning tool being located at an angle to the axis of rotation of the article and to the line of advancement of said tool, the two tools being located for simultaneous action upon different parts of the article, and means for moving the tool mechanism in a curved path so that each turning tool travels in a curved path and tangentially relative to the surface of the article and progressively engages the article at one part of its height and successively thereafter engages other parts of its height whereby the surface of the article is progressively turned.

5. A machine for turning articles of clay-ware, comprising a main support, a rotatable turret on the main support, means for step-wise rotating the turret, article supporting rotatable chucks on the turret for travel therewith from station to station, means for rotating the chucks, a first turning tool mechanism mounted on the main support adjacent a first turret station for movement in a curved path, a first profiled turning tool carried by said first tool mechanism in a curved path tangential to and intersecting the surface of an article positioned at said first station, said first tool being positioned on said first tool mechanism so that it is located at an angle to the line of its tangential advancement whereby it acts progressively upon the article along the height of the article, a second and finishing tool mechanism mounted on the main support adjacent a second turret station for movement in a curved path, a second and profiled finishing tool carried by said second tool mechanism in a curved path tangential to and intersecting the surface of an article positioned at said second station whereby it can perform a surface finishing operation on an article roughly turned at said first station and thereafter advanced to said second station, and means for concurrently moving said first and second tool mechanisms and including parts whereby the second and finishing tool is moved tangentially at a greater speed than the first tool.

6. A machine for turning articles of clay-ware, comprising a main support, a rotatable turret on the main support, means for step-wise rotating the turret, article supporting rotatable chucks on the turret for travel therewith from station to station, means for rotating the chucks, a first turning tool mechanism mounted on the main support adjacent a first turret station for movement in a curved path, a first profiled turning tool carried by said first tool mechanism in a curved path tangential to and intersecting the surface of an article positioned at said first station, said first tool being positioned on said first tool mechanism so that it is located at an angle to the line of its tangential advancement whereby it acts progressively upon the article along the height of the article, a second and finishing tool mechanism mounted on the main support adjacent a second turret station for movement in a curved path, a second and profiled finishing tool carried by said second tool mechanism in a curved path tangential to and intersecting the surface of an article positioned at said second station whereby it can perform a surface finishing operation on an article roughly turned at said first station and thereafter advanced to said second station, and means for concurrently moving said first and second tool mechanisms and including parts whereby the second and finishing tool is moved tangentially at a greater speed than the first tool.
